CLAIM

The ornamental design for an anti-theft assembly for video game cabinet access doors, as shown and described.

DESCRIPTION

FIG. 1 is a front elevational view of an anti-theft assembly for a video game cabinet showing my new design, the rear being plain and unornamented;

FIG. 2 is a top plan view thereof;

FIG. 3 is a left side elevational view thereof; and FIG. 4 is a top, front and right side perspective view thereof, the hinge portions being shown in their installed and hidden position and the broken line showing of a pair of video game cabinet access doors being for illustrative purposes only and formin no part of the claimed design.

FIG. 1

FIG. 2

FIG. 4

FIG. 3
